NECK PIECE

Maria K. Hohn, 20980 Morewood Parkway,
Rocky River, Ohio 44116

Filed Jan. 28, 1974, Ser. No. 437,323

Term of patent 14 years

Int. Cl. D2—05

U.S. Cl. D2—347

FIG. 1

FIG. 2

FIG. 1 is a top plan view of a neck piece showing my new design; and

FIG. 2 is a front perspective view with the ends inverted from their position in FIG. 1.

I claim:

The ornamental design for a neck piece, as shown and described.
